(57) **CLAIM**

The ornamental design for a contactless token with aperture, as shown and described.

DESCRIPTION

FIG. 1 is a perspective view of a first embodiment of the contactless token with aperture showing the new design;

FIG. 2 is a top plan view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a bottom plan view thereof;

FIG. 8 is a perspective view of a second embodiment of the contactless token with aperture showing the new design;

FIG. 9 is a top plan view thereof;

FIG. 10 is a front elevation view thereof;

FIG. 11 is a rear elevation view thereof;

FIG. 12 is a left side elevation view thereof;

FIG. 13 is a right side elevation view thereof;

FIG. 14 is a bottom plan view thereof;

FIG. 15 is a perspective view of a third embodiment of the contactless token with aperture showing the new design;

FIG. 16 is a top plan view thereof;

FIG. 17 is a front elevation view thereof;

FIG. 18 is a rear elevation view thereof;

FIG. 19 is a left side elevation view thereof;

FIG. 20 is a right side elevation view thereof;

FIG. 21 is a bottom plan view thereof;

FIG. 22 is a cross-sectional view thereof, taken along line 22—22 of FIG. 16;

FIG. 23 is a perspective view of a fourth embodiment of the contactless token with aperture showing the new design;

FIG. 24 is a top plan view thereof;

FIG. 25 is a front elevation view thereof;

FIG. 26 is a rear elevation view thereof;

FIG. 27 is a left side elevation view thereof;

FIG. 28 is a right side elevation view thereof;

FIG. 29 is a bottom plan view thereof; and,

FIG. 30 is a cross-sectional view thereof, taken along line 30—30 of FIG. 24.
